US0D1084028S

(12) **United States Design Patent** (10) **Patent No.:** **US D1,084,028 S**
Leung et al. (45) **Date of Patent:** **** Jul. 15, 2025**

(54) **DISPLAY SCREEN OR PORTION THEREOF WITH A GRAPHICAL USER INTERFACE**

(71) Applicant: **Chime Financial, Inc.**, San Francisco, CA (US)

(72) Inventors: **Melissa Mar Leung**, San Francisco, CA (US); **Ruslan Mirzayev**, Dubai (AE); **Graham Eschrich**, San Francisco, CA (US); **Stefan Cirkovic**, Novi Sad (RS); **Iching Cheng**, San Francisco, CA (US); **Pichamon Chamroenrak**, San Francisco, CA (US); **Samantha Berg**, San Mateo, CA (US); **Taron Ghazaryan**, Oakland, CA (US)

(73) Assignee: **Chime Financial, Inc.**, San Francisco, CA (US)

(**) Term: **15 Years**

(21) Appl. No.: **29/951,587**

(22) Filed: **Jul. 10, 2024**
